(57) **CLAIM**

We claim the ornamental design for a collared electrode assembly for a medical probe, as shown and described.

DESCRIPTION

FIG. 1 is a perspective view of a collared electrode assembly for a medical probe.

FIG. 2 is an enlarged view of the portion of the design of FIG. 1 within the circle labeled 2.

FIG. 3 is a front elevational view of the collared electrode of FIG. 1.

FIG. 4 is a rear elevational view of the collared electrode of FIG. 1.

FIG. 5 is a top plan view of the collared electrode of FIG. 1.

FIG. 6 is a bottom plan view of the collared electrode of FIG. 1; and,

FIG. 7 is a right side elevational view of the collared electrode of FIG. 1, wherein the left side elevational view is a mirror image thereof.

The collared electrode assembly is shown with a symbolic break in its length. The appearance of any portion of the article between the break lines forms no part of the claimed design. The dot-dash-dot broken lines in FIGS. 1 and 2 depict the boundary of the enlarged view and form no part of the claimed design. The dashed lines in the drawings depict portions of the collared electrode assembly for a medical probe that form no part of the claimed design.

1 Claim, 4 Drawing Sheets
